(57) **CLAIM**

The ornamental design for an air dryer reservoir, as shown and described.

DESCRIPTION

FIG. 1 is a perspective view of an air dryer reservoir of the present invention;

FIG. 2 is a side view of an air dryer reservoir shown in FIG. 1;

FIG. 3 is a front view of an air dry reservoir shown in FIG. 1;

FIG. 4 is a side view of an air dryer reservoir shown in FIG. 1;

FIG. 5 is a back view of an air dryer reservoir shown in FIG. 1;

FIG. 6 is a top view of an air dryer reservoir shown in FIG. 1; and,

FIG. 7 is a bottom view of an air dryer reservoir shown in FIG. 1.

The portions of the Figures shown in phantom lines are not part of the claimed design but are for illustration only.

1 Claim, 4 Drawing Sheets
